UNITED STATES PATENT OFFICE

147,341

DESIGN FOR A SPEAKER

Richard S. Latham, Chicago, Ill., assignor to The
Hallcrafters Co., a corporation of Illinois

Application November 30, 1945, Serial No. 124,240

Term of patent 14 years

(Cl. D26—14)

To all whom it may concern:

Be it known that I, Richard S. Latham, a citizen of the United States, residing at Chicago, in the county of Cook and State of Illinois, have invented a new, original, and ornamental Design for a Speaker, of which the following is a specification, forming part thereof, characteristic features of my design being shown in full lines.

Figure 1 is a front elevational view of a speaker embodying my design;

Figure 2 is a top plan view of such speaker;
Figure 3 is a back view of the speaker;
Figure 4 is a side elevational view looking from the right of Figure 1; and
Figure 5 is a front perspective view of the speaker shown in Figure 1.

I claim:

The ornamental design for a speaker, as shown.

RICHARD S. LATHAM.
